UNITED STATES PATENT OFFICE.

PAUL H. McCAIN, OF CHICAGO, ILLINOIS.

THREADING-MACHINE.

1,188,461.

Specification of Letters Patent. Patented June 27, 1916.

Application filed April 16, 1914. Serial No. 832,178.

To all whom it may concern:

Be it known that I, PAUL H. McCAIN, a citizen of the United States, residing at Chicago, in the county of Cook and State of Illinois, have invented certain new and useful Improvements in Threading-Machines, of which the following is a specification.

This invention relates to a thread-forming machine, more particularly described as a continuous threading machine designed and adapted to make a continuous thread on a bar or member of any length.

The principal object of the invention is to provide a simple machine of this class which may be used for forming threads of different pitch and for accommodating members of different sizes.

For the attainment of these ends and the accomplishment of other new and useful objects, as will appear, the invention consists in the features of novelty in the construction, combination and arrangement of the several parts generally shown in the accompanying drawings and described in the specification, but more particularly pointed out in the appended claims.

In the drawings, Figure 1 is a plan view of a machine constructed in accordance with the principles of my invention; Fig. 2 is an elevation, partly in section, on line 2—2 of Fig. 1, and Fig. 3 is a sectional view on the line 3—3 of Fig. 1.

This invention relates to a machine for forming a thread on the outside of a member, not by cutting or actually removing any of the material from a member, but by impressing a certain portion and building up a space between, thereby forming a thread of any desired shape in which the deepest portion of the thread is less than the diameter of the member and the external diameter of the thread is somewhat greater than the diameter of the member. Of course, it is possible to provide cutters or threading members which, instead of rolling a thread upon the member, as the present process may be briefly described, actually cuts and removes a portion of the material. The present threading members, however, by their rolling action on the opposite sides of the member to be threaded not only form the threads thereon but also positively feed the member to be threaded in the proper direction with the proper feeding action.

Referring now more particularly to the drawings, a base member 1 is formed with a slot 2 in which a pair of bearings 3 are adjustable. One of the bearings is adjustable in the slot by means of a wedge 4 and an adjusting screw 5, and the other bearing member is adapted for more rapid adjustment by means of an eccentric shaft 6 controlled by an arm 7 having a controlling dog 8 to engage any one of the teeth of a segment 9 secured to the base member.

A support 10 has a journal portion 11 fitting closely in each bearing member 3, and the bearing member is formed with a split adjustable gripping portion 12 by means of which the journal of the support may be held firmly in the bearing to prevent its rotation therein after adjustment. A plate 13 is secured to the end of the support to hold it longitudinally in place in the bearing and the adjacent edges of each support are provided with graduations 14 to indicate the rotated position of the support with respect to the bearing.

Projecting inwardly from each bearing is a support provided with a perforated portion 15 with its axis at right angles to the axis of the bearing, and mounted for free rotation in the perforation is a sleeve 16 and a shoulder 17 at one end and adjusting device 18 for holding it in place within the perforation. Secured to each sleeve 16 by means of a plate 19 is a threading member 20, the members having alternately disposed thread-forming grooves; that is, a thread-forming projection on one member is opposite a thread-forming groove on the other member.

Secured to each bearing member 3 is a fixed bracket 21 in which a shaft 22 is mounted, one end of which extends substantially through the sleeve 16 to a point adjacent the other end thereof and to a point substantially in line with the axis of the bearing. Connecting the shaft and the sleeve member at this end is a universal connection, designated generally by the reference numeral 23, constructed in any well known manner by means of which the sleeve 16 may be rotated when the shaft 22 is rotated. The internal diameter of the sleeve 16 is considerably greater than the external diameter of the shaft so that the support 10 may be rotated to a considerable degree before the end of the sleeve, which is not connected with the shaft, will contact

therewith. Preferably the sleeve is tapered from the end which is connected with the shaft. In order to rotate both of the shafts 22 a common driving shaft 24 is provided with worms 25 and each shaft 22 is provided with a gear 26 meshing with the worm for rotating the shaft.

Secured to the base member 1 at one side thereof and intermediate the bearing members 3 is a support 27 formed at its upper end with a trough or groove 28 in which a bar 29 or member to be threaded is seated for the threading action.

In operation the member to be threaded is inserted between the threading members 20, which are oppositely inclined, for the reason that they operate on opposite sides of the member to be threaded and are inclined the same amount in opposite directions from a vertical center line for the purpose of determining the inclination of the thread to be formed on the member, and the rolling action or contact of these members with the opposite sides of the member to be threaded not only forms a thread by forming a ridge of material between two grooves, but also, by their rotation, feeds a member to be threaded forwardly in accordance with the pitch of the thread to be formed. One of the bearing members 2 is fixed in position by means of the wedge adjusting device, and the other bearing member is provided with means for moving it quickly into and out of position by simply throwing the hand lever 7 so that the dog thereof contacts with any one of the teeth of the segment so that the bearing member and the threading member carried thereby are readily movable into and out of position for making threads of the same pitch from different sizes of bars. Of course, to vary the inclination of the thread cut, it is necessary to change the inclination of both of the threading members 20 in opposite directions from a vertical center line, the amount of change necessary to produce a thread of any given inclination being indicated by the graduations 14.

A long bar may be continuously threaded by this machine for the reason that the fixed brackets 21 are spaced apart, as shown more clearly in Fig. 2, in order to permit a threaded bar or rod to pass between the fixed brackets if it is long enough to extend from the threading rolls to the adjacent edges of the brackets, as shown in Fig. 1.

It is obvious that others skilled in the art to which this invention appertains may make various changes in the construction, combination and arrangement of the several parts within the scope of the claims.

What I claim is:

1. A continuous threading machine comprising rotatable threading rollers with oppositely disposed threads, and rotatable

means having axes transverse to the axes of the rollers to incline the rollers to change the angle of inclination of the thread.

2. A threading machine comprising threading rollers having oppositely disposed threads adapted to contact on the opposite sides of a member to be threaded, and rotatable means for independently inclining the rollers to vary the angle of inclination of the thread.

3. In a threading machine, the combination of a pair of threading members adapted to contact on opposite sides of the members to be threaded, means for rotating each member, a separate rotatable support for each member for adjusting the inclination thereof, and a universal connection between the rotating means and each member whereby it may be inclined in the support.

4. In a threading machine, the combination of oppositely disposed threading members adjustable toward and from each other and adapted to contact on opposite sides of a member to be threaded, means for operating each threading member, and a rotatable support for each threading member by means of which the inclination can be changed independently for varying the angle of inclination of the thread.

5. A threading machine comprising threaded members adjustable toward and from each other, a support for the members to be threaded whereby the threading members contact the opposite sides of the member to be threaded, means to rotate the threading members, and a rotatable support for each of the threading members whereby their inclination may be independently adjusted for varying the angle of inclination of the thread.

6. In a threading machine, the combination with oppositely disposed threading members, of a shaft for rotating each member, a universal connection between each shaft and its member, a bearing for each member, and a support rotatable in each bearing for adjustment therein adapted to carry the member with its axis at right angles to the axis of the bearing.

7. In a threading machine, a pair of adjustable bearings movable toward and from each other, a support mounted in each bearing having a perforated portion with its axis at right angles to the axis of the bearing, a sleeve rotatable in the perforated portion, a threading member mounted upon the sleeve, a shaft extending through the sleeve with a space between it and the sleeve, and a universal connection between the shaft and the sleeve whereby the inclination of each threading member may be changed with respect to the shaft for varying the angle of inclination of the thread made.

8. In a threading machine, a pair of supports, bearings movable toward and from

- each other in which the supports are adjustably rotatable, the bearings and supports being provided with graduations to indicate the position of the supports in the 5 bearings, and threading members mounted upon and movable with the supports about an axis substantially at right angles to the axis of the bearings and having oppositely disposed threads adapted to engage a member 10 to be threaded on opposite sides thereof.
9. In a threading machine, bearings movable toward and from each other having means for tightening the bearings, supports each having a threaded portion rotatable in 15 the bearings with means thereon for indicating the position with respect to the bearing, and threading members mounted upon the support for free rotation about an axis substantially at right angles to the axis of 20 each bearing, the supports being rotatable in the bearings for varying the inclination of the threading members whereby threads of predetermined angle of inclination may be formed.
- 25 10. In a threading machine, the combination of a pair of perforated supports adjustable toward and from each other, a threading member carried by each support, a shaft extending through the perforation 30 of each support and freely movable therein, a support for holding each shaft in fixed position, and a universal connection between each shaft and the corresponding threading member whereby its perforated support may 35 be oscillated with respect to the shaft for varying the inclination of the threading member.
11. In a continuously operable threading 40 machine, the combination of a pair of rotatable threading members having thread forming grooves oppositely disposed with respect to each other and being adjustable toward and from each other on opposite sides of the member to be threaded, and a 45 fixed support for seating a member to be threaded whereby it may be fed continuously between the threading members to thread the members from end to end.
12. In a threading machine, the combination 50 of a pair of rotatable and adjustably inclinable members, with similar thread-forming grooves in the outer edge thereof adapted to engage the opposite sides of a member to be threaded and inclined in opposite directions with respect to each other whereby, in rotating, the opposite sides of 55 the member to be threaded will be engaged forming a thread on said member and for feeding the threaded member forwardly in accordance with the inclination of the 60 threading members with respect to each other whereby a member may be threaded from end to end if desired.
13. In a threading machine, the combination 65 with a base member, of bearing mem-
- bers slidable on said base member toward and from each other having means for tightening the bearing, a support rotatable in each bearing adjustable with respect thereto adapted to be held in place by said 70 tightening means and each having a perforated portion, a sleeve mounted in said perforated portion, a fixed shaft movable within the bearing and extending within the sleeve, thread-forming members, one on each sleeve 75 with oppositely disposed thread-forming portions adapted to engage opposite sides of a member to be threaded and rotatable about the axis of said bearing to vary the angle of inclination thereof, means to secure each of 80 said members to the corresponding sleeve, a universal connection between each shaft and the corresponding sleeve whereby the support can be tilted for varying the angle of inclination, means for rotating the shafts, 85 and a support fixed to the base member for holding a member to be threaded in position to be engaged by both of said threading members and for preventing the member to be threaded from being moved out of proper 90 engaging position.
14. In a threading machine, the combination with a base member, of bearings adjustable toward and from each other on said base member, supports rotatably mounted 95 in each bearing member, thread-forming rollers carried by the supports, means for rotating the rollers, and means for separately adjusting both of said bearing members toward and from each other. 100
15. In a threading machine, the combination with a base member, of bearings adjustable toward and from each other on said base member, supports rotatably mounted in each bearing member, thread-forming 105 rollers carried by the supports, means for rotating the rollers, a support for a member to be threaded intermediate the bearings, means for adjusting and fixing the position of one bearing member with respect to the 110 support for the member to be threaded, and means for varying the position of the other bearing with respect to the support for the member to be threaded whereby this said other bearing may be freely moved to and 115 fro.
16. In a threading machine, a pair of bearings movable adjustably toward and from each other, a support rotatably adjustable in each bearing, a thread-forming roller 120 rotatable in each support, and means for rotating the said rollers comprising a shaft fixed with respect to each bearing and connected to each roller, a common shaft at right angles to the other shafts, and driving 125 connections one between the common shaft and each of the other two shafts.
17. In a threading machine, a pair of bearings movable adjustably toward and from each other, a support mounted in each 130

- bearing, a threading member mounted in each support, a bracket fixed to each bearing, a shaft journaled in each bracket, means to connect each shaft with one of the 5 threading members, a common shaft extending through the brackets, and a worm and gear connection between the common shaft and each of the shafts for rotating the separate threading member shafts.
- 10 18. In a threading machine, the combination of oppositely disposed threading members adjustable toward and from each other and adapted to contact on opposite sides of a member to be threaded, means for operating each threading member, a rotatable sup-

port for each threading member by means of which the inclination can be changed for varying the angle of inclination of the thread, and a scale for indicating the angular position of each support whereby the 20 angle of inclination of the thread to be cut can be predetermined.

In testimony whereof I have signed my name to this specification, in the presence of two subscribing witnesses, on this 13th day 25 of April A. D. 1914.

PAUL H. McCAIN.
